LIQUID FUEL BURNER

Filed Oct. 19, 1934

UNITED STATES PATENT OFFICE

2,086,639

LIQUID FUEL BURNER

Leslie H. Rees, Denver, Colo.

Application October 19, 1934, Serial No. 749,057

1 Claim. (Cl. 158—96)

This invention relates to a liquid fuel burner and has for its principal object, the provision of a burner in which liquid fuel will be admixed, atomized, and dispersed in an exceedingly dispersed condition in a highly porous, fire resisting, dispersion medium so that the fuel will be efficiently prepared and converted into a highly inflammable, easily combustible condition which will result in efficient combustion.

Another object of the invention is to provide means for introducing and dispersing either or both air and water into the highly dispersed fuel to assist in the combustion thereof.

A further object is to provide a dispersing medium for use in liquid fuel burners which will be low in cost, and economical to use; which will not pack but will remain highly porous; which will efficiently act to break up the incoming combustion constituents into a rich combustible mixture; and which will not be affected by the liquids used or heat generated in the burner.

A still further object is to provide a burner top for supporting the combustion which will be highly porous, fire resistant, and easily manufactured to suit any desired conditions of use.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:—

Fig. 1 is a plan view of a burner in which the invention is embodied.

Fig. 2 is a cross-section of the burner of Fig. 1, taken on the line 2—2. In Fig. 2 the burner is illustrated installed in a base or housing of refractory protective and supporting material.

Fig. 3 is a detail side view, partly in section, illustrating a flame spreading cap which may be employed with the burner.

The invention employs a cup-like container 10, which may be of any suitable size, depending upon the particular installation in which the burner is to be used, and formed of any suitable fire resisting material. It is preferred to employ a relatively thick-walled, cast iron cylinder for the container 10, provided with a closed bottom 11.

The major portion of the container 10 is filled with a loose mass or bed of any suitable coarse

granulated porous, fireproof material of a nature which will not pack, but will form a porous mass capable of withstanding a high temperature and having a relatively high percentage of voids or interstices.

The most satisfactory material for this purpose has been found to be roasted vermiculite. Vermiculite is prepared by roasting an ore of the altered mica type such as jefferisite or zonolite, kerrite, maconite, etc., or any other ore containing a high percentage of altered mica. Such an ore when roasted, expands to many times its original volume, owing to the separation and corrugation of the mica sheets or layers. The resultant, light, highly porous product has been found highly satisfactory for the present invention. This material can be ground to any desired degree of fineness, and forms a light, fireproof, highly porous mass. Granules of this material varying in size from $\frac{1}{8}$ to $\frac{1}{4}$ inch has been found to be most satisfactory for the present purpose.

The loose granulated material 12 is held in place and covered by means of a porous cap 13. The cap 13 may have any desired form, but is preferably formed with an inwardly inclined conical border 14 leading to a semi-spherical depression 13'. This cap may be formed of any suitable porous fireproof material. A very satisfactory material has been found to be a mixture of coarse broken pieces of baked fire clay, mixed with vermiculite bound together with a suitable binder such as a plaster paris cement.

The cap 13 can be moulded or cast directly in place upon the loose vermiculite in the container 10 by first placing a convex disc of wire screen 15 over the vermiculite, thence pouring the above described mixture thereon, and molding the same to the required shape. After setting, this mixture produces a fireproof cap of high porosity.

The burner can be used by simply pouring alcohol or other volatile combustible liquid into the depression 13' of the cap, and allowing it to percolate therethrough into the interstices of the vermiculite until the desired amount has been completely absorbed. The wet surface of the cap is then ignited, producing a flame thereabove. This flame heats the cap 13 and the upper portion of the vermiculite, causing a vaporization and gasification of the fuel, which, together with capillary attraction, forces it through the porous top into the flame. Such a procedure, however, is not continuous in operation.

For a continuous operation in a permanent installation, a liquid fuel pipe 16 is run through the

wall of the container 10, preferably terminating in a suitable distributing head 17. The fuel is fed continuously into the porous interior through the pipe 16 so as to continuously feed the flame above the cap 13.

For installations requiring a higher temperature, an air pipe 18 may be run into the container 10, adjacent the bottom thereof, and provided with suitable perforations 19 for distributing air under pressure through the porous mass to force the vaporizing fuel through the cap thereof, and to supply additional combustion oxygen. During its passage through the porous mass the air will be brought into intimate contact with, and become highly dispersed in the fuel so as to provide a highly efficient mixture.

Still higher temperatures are obtainable by running a water pipe 20 through the wall of the container 10 above the air pipe 18, and providing the water pipe with any suitable distributing head 21. The air and capillary attraction forces the water toward the top of the container where it admixes with and vaporizes with fuel. A mixture of steam, air and fuel is then forced through the cap, resulting in an exceedingly high temperature flame.

It is believed that the water vapor in steam coming in contact with the highly heated vermiculite, and the heated cap 13, in close association with the hydro-carbon of the fuel, forms a mixture of carbon monoxide and hydrogen or "water gas" ($\text{CO}+2\text{H}$) in direct contact with the flame. Both of these constituents are of course highly inflammable and greatly increase the heat of the resulting flame.

The supply pipes leading into the container 10 are of course provided with suitable valves, such as indicated at 22 and 23. In permanent installations, the container may be embedded in masonry 40 or a fire clay housing, such as indicated at 24.

In some installations, especially in hot air fur-

naces, it is desirable to have the flame spread outwardly so as to heat the walls of the firebox. This may be accomplished by placing a flame spreader, such as indicated at 25, Fig. 3, over the cap 13. The flame spreader illustrated is formed of heat resisting material of high fusing point and consists of a relatively flat projecting top from which a perforated cylinder or sleeve 26 projects downwardly. The sleeve 26 is formed with suitable perforations 27. This flame spreader is positioned in the broken line position of Fig. 2, and the gas rising from the mid-portion of the cap 13 enters the sleeve 26, passes through the perforations 27, and burns as a flame under the spreading cap 25.

The burner, even when used with the heavier fuel oils, produces a practically colorless, noiseless flame of exceedingly high temperature. This flame can be very accurately controlled by manipulation of the air valve 23. The burner can be lighted without preheating or generation. The heated porous particles soon form an ideal generator for the fuel.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:—

A liquid fuel burner comprising: a container; a loose bed of small particles of roasted vermiculite in said container; a porous cap of refractory fire resisting material holding said material in place; means for feeding liquid fuel into said bed; an air conduit opening into said container for feeding air upwardly through said bed; and a water conduit leading into said container.
